J. BERG.
LIGHTING AND IGNITION DEVICE.
APPLICATION FILED SEPT. 18, 1912.

Patented Oct. 28, 1913.

UNITED STATES PATENT OFFICE.

JOHN BERG, OF CHICAGO, ILLINOIS, ASSIGNOR TO METAL SPECIALTIES MANUFACTURING COMPANY, OF CHICAGO, ILLINOIS, A CORPORATION OF ILLINOIS.

LIGHTING AND IGNITION DEVICE.

1,076,943.

Specification of Letters Patent.

Patented Oct. 28, 1913.

Application filed September 18, 1912. Serial No. 720,963.

To all whom it may concern:

Be it known that I, JOHN BERG, a citizen of the United States, residing at Chicago, in the county of Cook and State of Illinois, have invented a new and useful Improvement in Lighting and Ignition Devices, of which the following is a specification.

This invention relates particularly to electric lighting and ignition devices.

10 In the preferred form, it comprises a combination exploring lamp and cigar lighter, such a device being particularly useful in connection with automobiles, motorcycles and the like.

15 The primary object of the invention is to provide a device of the character indicated of improved and simplified construction and improved operation.

20 The invention is illustrated in its preferred embodiment in the accompanying drawing, in which;

Figure 1 is a side elevational view of a combination exploring lamp and cigar lighter constructed in accordance with my invention; Fig. 2, a longitudinal sectional view taken as indicated at line 2 of Fig. 3, in which, however, the igniter socket and lamp socket and the igniter and lamp mounted therein are shown in elevation; Fig. 3, 25 an enlarged sectional view taken as indicated at line 3 of Fig. 2; Fig. 4, a broken elevational view showing a detail of the circuit-closing button which operates the lamp; Fig. 5, a plan view of the igniter detached from the handle, the perforate mica disk thereof being shown brokenly; Fig. 6, an enlarged broken sectional view showing the manner in which the lamp socket and igniter socket are carried on the internal 30 mounting employed, the section being taken as indicated at line 6 of Fig. 5; Fig. 7, a sectional view of the igniter taken as indicated at line 7 of Fig. 5; Fig. 8, a sectional view of the igniter socket taken as indicated 35 at line 8 of Fig. 6; and Fig. 9, an elevational view showing a modification of the socket-mounting as when the device is to be used for one purpose only.

Referring to Figs. 1 to 8 inclusive, the device comprises, in its preferred embodiment, a handle A; an internal socket-mounting B housed in said handle and equipped with a lamp-socket B¹ and an igniter-socket B²; a lamp bulb C mounted in the socket B¹; and

an igniter or cigar-lighter D mounted in the 55 socket B².

The tubular or hollow handle A has a chamber or bore 1 which accommodates the mounting B. The rear end of the handle has a reduced opening 2 through which the 60 conductors 3 and 4, which may connect with any suitable source of electric energy such as a battery, enter the handle. The bore 1 is of suitable size at the other end of the handle to receive the lamp-socket B¹ snugly therein. 65

The socket-mounting B preferably comprises the metal bars or forks 5, 6 and 7, of which the bar 5 carries the lamp-socket and igniter-socket, while the forks 6 and 7 serve, respectively, as circuit-closers for the lamp 70 and igniter. The manner of mounting the sockets on the bar or fork 5 will be readily understood by reference to Figs. 2, 3, 6 and 8. The bar 5 has its forward end 8 bent at right-angles to its body-portion and extending through a lateral slot 9 in the base-portion of the socket B¹. The socket B¹, which comprises a thin internally threaded metal shell, has an inturned bottom flange 10, in contact with which the member 8 lies. The 80 parts are secured together by a screw 11 which passes through insulating washers 12 and 13, one of which is disposed in the socket B¹ above the member 8, while the other is disposed below or back of the bottom flange 85 10. The screw passes through a threaded perforation in a metal member 14 provided with a contact arm 15. The head of the screw serves as an internal central terminal, while the socket B¹ is in electric connection 90 with the arm 5 by which it is carried.

The socket B² is mounted on the outer side of the arm 5 near the bent extremity 8 thereof. It comprises an internally threaded metal shell having its inner or base portion 95 equipped with an inturned flange 16. A clip or washer 17 is inserted in the socket, and has a shank 18 which projects laterally through a slot 19 in the base portion of the socket and is turned or bent to engage the 100 edge portion of the bar 5. A screw 20 connects the parts, the screw having its shank threaded into a nut 21 equipped with a contact-arm 22. Insulation washers 23 and 24 serve to insulate the screw and contact member 22 from the other parts. The head of the screw 20 is disposed in the socket B² and affords an internal central terminal. 105

The electric light bulb C, when threaded into the socket B¹, makes contact in the usual manner with the shell of the socket B¹ and the head of the screw 11. The igniter 5 makes contact in a similar manner with the shell of the socket B² and the head of the screw 20, as will be understood from the construction which will now be described.

The igniter D preferably comprises a 10 metallic cup 25 having its base portion 26 fitted with an externally threaded tubular shank 27 adapted to screw into the socket B²; insulating material 28 filling the tubular shank 27 and partially filling the cup 25; a central post or conductor 29 whose lower end projects below the shank 27 and affords a central terminal adapted to contact with the head of the screw 20; an outer post 30 rising from the base portion of the 15 cup 25 with which it is in electric contact; a resistance coil 31 of convolute form, having its inner end attached to the central post 29 and having its outer end attached to the post 30; a perforate disk 32 of mica, or the like, disposed above the resistance coil; and 20 a washer or retainer ring 33 serving to hold the mica disk in place.

It is preferred to provide the upper or 25 outer portion of the post 29 with a bore in which the inner end of the resistance coil 31 is inserted and secured by a wedging pin 34. Likewise, the stud or post 30 is provided with a bore into which the outer end of the 30 resistance coil is extended and secured by a wedging pin 35. The insulating material 28 may be introduced while in plastic form, and it is preferred to set in said plastic material radially disposed mica strips 36 whose upper edges project somewhat above 35 the outer surface of the material 28 and serve to support the convolutions of the resistance coil. It will be noted that a small air-space 37 is thus provided below the resistance coil, so that it will be unnecessary 40 to heat the material 28 when the device is being used for cigar lighting purposes.

The contact member 6 is adapted to be 45 pressed inwardly against the contact member 15 to light the lamp by means of a push-button 38; and the contact member 7 is adapted to be pushed inwardly into contact with the contact member 22 by means of a 50 push-button 39. These buttons project through lateral openings 38^a and 39^a in the handle. It is preferred to partially encircle 55 the handle with a combination name-plate and button-retaining-plate 40, which may be secured, as by screws 41. The button 39 is adapted to be pressed inwardly so that the 60 circuit for the cigar-lighter will remain closed only so long as the button is held pressed inwardly. The button 38 is adapted to be pressed inwardly and shifted, so that the contact member 6 can be locked in contact 65 with the contact member 15, thus keeping

the lamp lighted as long as desired. To this end, the ferrule or curved plate 40 is provided with a T-slot 42; and the outer portion of the button 38 is provided with a circumferential slot 38^b adapted to move in the restricted portion of the opening when the button is shifted, thereby to lock the button in its inwardly pressed position. It will be understood that the members 6 and 7 are resilient, so that they will force the buttons outwardly when free to do so. As clearly appears from Fig. 3, the buttons are angularly disposed with relation to each other, but are located in substantially the same transverse plane to facilitate manipulation.

In the modification shown in Fig. 9, B^a represents a mounting equipped with a single socket B^b which corresponds with the socket B¹ shown in Fig. 6. The socket B^b is adapted to receive either the igniter B or the lamp-bulb C, as may be desired. It will be noted that this construction is like the construction already described, except that the socket B² is dispensed with, and the fork or contact member 7 is dispensed with.

It will be noted from Fig. 2 that the conductors 3 and 4 are connected with the extremities of the bars 5 and 6, and that the bars 5 and 6 are separated from each other by insulation strips 43. The shank of the member 7 is in electrical contact with the shank of the member 6. It will be understood that the member 5 serves with either the fork 6 or the fork 7 to establish a circuit, depending upon whether the electric light or the igniter is being used.

It may be added that the conductors 3 and 4 may be inserted wholly through the handle before being connected with the members 5 and 6, after which the mounting may be drawn to its proper place in the handle. The handle is fitted with a reflector 44 which has a tubular shank 45 fitted on the front 105 end of the handle and removably secured by means of screws 46.

From the foregoing description, it will be understood that the improved construction is simple and capable of ready manipulation, either as an exploring lamp or as a 110 cigar lighter.

The foregoing detailed description has been given for clearness of understanding only, and no undue limitation should be understood therefrom, but the appended claims should be construed as broadly as 115 permissible in view of the prior art.

What I regard as new and desire to secure by Letters Patent is:

1. In a device of the character set forth, the combination with a hollow handle-piece of a lamp-socket at one end thereof, a lateral socket disposed near the lamp-socket, a mounting for said sockets within the handle, 130

- circuit-closers corresponding with the two sockets and laterally projecting actuating devices for said closers.
2. In a device of the character set forth, the combination of a hollow handle-piece, a lamp-socket disposed axially thereof at one end of the handle, a lateral socket, a mounting in the handle carrying said sockets and affording a conductor, central terminals insulatingly mounted within the sockets and provided within the handle with contact members, spring contact members insulatingly carried by said mounting, and laterally projecting actuating buttons for said contact members.
3. In a device of the character set forth, the combination with a hollow handle-piece of a lamp-socket at one end thereof, a lateral socket disposed near the lamp-socket, a mounting for said sockets within the handle, circuit-closers corresponding with the two sockets, a laterally projecting push-button adapted to close the circuit corresponding with the socket, a laterally projecting push-button adapted to actuate the circuit-closer corresponding with the lamp-socket, and means for securing said last-named push-button in the circuit-closing position.
4. In a device of the character set forth, the combination of a hollow handle, a bar therein constituting a mounting and equipped at one end with a lamp-socket disposed axially of the handle and equipped laterally with a socket projecting laterally through the handle, central terminals insulatingly mounted in said sockets and equipped with in the handle with contact members, circuit-closers insulatingly carried by said mounting, and push-buttons projecting laterally through the handle and adapted to press either one of said circuit-closers to the circuit-closing position.
5. A device of the character described comprising a hollow handle, a metallic bar therein constituting a mounting, a lamp-socket carried by one end of said bar and disposed axially of the handle at one end thereof, a laterally extending socket carried by said bar, central terminals insulatingly mounted in said sockets and equipped within the handle with contact members, spring arms insulatingly mounted on said bar and serving as circuit-closers, and laterally projecting push-buttons adapted to move the circuit-closers to the circuit-closing position.
6. A device of the character set forth comprising a hollow handle, a metal bar therein constituting a mounting, said bar having a laterally turned extremity, a lamp-socket mounted on said laterally turned extremity and in electrical contact therewith, a socket mounted on one side of said bar and in electrical contact therewith, central terminals in said sockets equipped within the handle back of said sockets with contact members, spring circuit-closing arms insulatingly carried by said bar, and means for moving either one of said circuit-closing arms to the circuit-closing position.
7. A device of the character set forth comprising a hollow handle, a metallic bar therein constituting a mounting, a lamp-socket disposed axially of the handle at one end thereof and carried by said bar, a laterally projecting socket carried by said bar, central terminals insulatingly mounted within said sockets and equipped within the handle with contact members, spring circuit-closing arms insulatingly mounted on said bar, a retainer-plate embracing the handle, and push-buttons projecting through said retainer-plate and adapted to move the circuit-closing arms to the circuit-closing position.
8. A device of the character set forth comprising a tubular handle, a mounting therein equipped at one end with an axially disposed lamp-socket and equipped adjacent thereto with a laterally extending socket, central terminals insulatingly mounted in said sockets and equipped back of the sockets with contact members, circuit-closers insulatingly carried by said mounting, means for actuating the circuit-closers, and electrical conductors extending through the rear portion of the handle and connected, one with said mounting and one with said circuit-closers.
9. A device of the character set forth comprising a tubular handle, an axially disposed lamp-socket at one end thereof, a laterally extending socket adjacent thereto, a mounting within the handle, terminals insulatingly mounted in said sockets and equipped back of the sockets with contact members, circuit-closers coacting with said contact members, a retainer-plate embracing the handle and equipped with perforations for push-buttons, one of said perforations having a restricted offset opening, and push-buttons projecting through said retainer-plate, one of said push-buttons having a recess adapted to move in the restricted portion of the corresponding opening, for the purpose set forth.
10. In a device of the character set forth, the combination of a hollow handle-piece, a mounting therein having a fork equipped with a tubular socket and having another fork serving as a contact-maker, a central terminal insulatingly mounted in said socket and equipped back of the base of the socket with a contact member, and a push-button projecting laterally from the handle and adapted to move said first-named contact member against said second-named contact member.
11. In a device of the character set forth, the combination of a tubular hand-piece, a

bar therein constituting a mounting, an axially disposed socket at one end of the handle and carried by said bar, a central terminal insulatingly mounted in said socket and 5 equipped back of the socket with a contact-member, a circuit-closer insulatingly mounted on the rear portion of said bar, and a lat-

erally projecting push-button mounted on said handle.

JOHN BERG.
